UNITED STATES PATENT OFFICE.

MICHAEL FERTL, OF SCHWABACH, NEAR NUEREMBERG, GERMANY.

PRESSURE-RELIEF APPARATUS FOR USE IN FERMENTATION PROCESSES.

1,205,086.

Specification of Letters Patent.

Patented Nov. 14, 1916.

Application filed May 7, 1914. Serial No. 837,018.

To all whom it may concern:

Be it known that I, MICHAEL FERTL, of Schwabach, near Nuremberg, Bavaria, Germany, have invented an Improvement in or 5 Relating to Pressure-Relief Apparatus for Use in Fermentation Processes, of which the following description, in connection with the accompanying drawings, is a specification.

- 10 It is known to use in the manufacture of beer and the like pressure relief apparatus in which mercury is carried in a bent tube through which the gasses generated by fermentation pass when they reach a sufficiently high pressure. In order to enable 15 the gases to escape without disturbing the mercury too much, a large number of stops are arranged in a staggered series one above another in the outlet branch of the tube. 20 These stops act as bubble breakers and subdivide the gas-bubbles rising through the mercury into a number of smaller bubbles which can rise more easily through the mercury. 25 This invention relates to an improved construction of such apparatus, and comprises the arrangement of ribs in the outlet branch containing the bubble breakers, the said ribs being disposed laterally of or between the 30 breakers which they divide into series and thus form rising conduits which inclose or pass through the series of breakers and are connected to the latter by slots. Owing to this construction, a very steady passage of 35 the gases through the branch is insured, and when an excessive increase of pressure takes place, a quick discharge of the gases is insured, without the column of mercury being greatly agitated. 40 A construction according to this invention is illustrated in the accompanying drawings in which—

Figures 1, 3 and 5 are front elevations, while Figs. 2, 4 and 6 are cross-sections 45 respectively on lines A—A, B—B and C—C, and Fig. 7 is a side elevation.

In the outlet branch comprising a box-like casing 2 covered by a transparent plate 6 and a frame 7—the said branch having at 50 the back the inlet branch 1 which communicates through the opening 8 with the box—are arranged in staggered series bubble

breakers 5 separated from each other by narrow intervals 4. According to this invention, in addition to the breakers, ribs are 55 provided which divide the former into series and at the same time form rising conduits communicating by slots with the series of breakers.

According to the construction shown in 60 Figs. 1 and 2, in the outlet branch, near one side, a zig-zag shaped rib 10 is arranged which forms with one wall of the box a rising conduit which is also filled with breakers and communicates through an opening 9 65 with the series of breakers separated.

According to the construction shown in 70 Figs. 3 and 4, laterally of, and between, the breakers zig-zag ribs 10' are arranged which also form rising conduits and communicate 70 by a slot 9' with the series of breakers divided off. The lateral ledges form with the wall of the box ziz-zag shaped conduits 11.

The construction shown in Figs. 5 and 6, has an arrangement of ribs 10'' straight at 75 one side and subdivided by slots 9''. The outer ribs are at a little distance from the wall of the box so that straight conduits 12 are produced, which like the conduit 12 formed by the central ribs, extend upward 80 and lead the gases to the outlet opening 3, while the liquid can flow back around the bubble breakers and through the openings in the ribs.

Having now particularly described and 85 ascertained the nature of my said invention and in what manner the same is to be performed, I declare that what I claim is:—

In a pressure relief apparatus of the character described, in combination, a casing, an 90 outlet branch in said casing, bubble breakers and ribs in said branch, said ribs forming with the wall of the casing a rising conduit passing through said breakers and communicating therewith by slots, and auxiliary 95 breakers in said conduit, substantially as described and for the purpose set forth.

In testimony whereof I affix my signature in presence of two witnesses.

MICHAEL FERTL.
